CLAIM

The ornamental design for a display screen or portion thereof with graphical user interface, as shown and described.

DESCRIPTION

This application is related to U.S. Provisional Patent Application No. 62/900,396 , entitled “Metamorphic Persistent Symbols Using Random Probability Distribution” and U.S. Provisional Patent Application No. 62/914,159 , entitled “Metamorphic Persistent Symbols Using Random Probability Distribution.”

The FIGURE depicts a display screen or portion thereof with graphical user interface.

The dashed broken line in the perimeter of the drawings illustrates a display screen or portion thereof and forms no part of the claimed design. The remaining dashed broken lines indicate portions that form no part of the claimed design.
